UNITED STATES PATENT OFFICE.

ISIDOR BROBERG, DECEASED, LATE OF LIDINGO-BREVIK, SWEDEN, BY GUNNAR LEONARD AMANDUS RAMSTEN AND ESTER BROBERG, ADMINISTRATORS, BOTH OF STOCKHOLM, SWEDEN, AND ERIK OTTO ERIKSSON, OF LIDINGO-BREVIK, AND BENGT SJÖLIN, OF TROLLHATTAN, SWEDEN, ASSIGNEES TO AKTIEBOLAGET LJUNGSTRÖMS ÅNGTURBIN, OF LIDINGO-BREVIK, SWEDEN, A CORPORATION.

CONDENSER FOR LOCOMOTIVES.

Application filed November 25, 1925, Serial No. 71,468, and in Sweden November 26, 1924.

Condensers for locomotives are usually of the type comprising an air cooled part consisting of condenser pipes or corresponding elements or similar members disposed on opposite sides of a vertical plane of symmetry through the condenser, said members being passed by air forced onwards by fans placed side by side. The cooling elements are usually arranged as to form, so to say, either the roof of the condenser or the sides thereof. The fans have usually been disposed horizontally behind one another in the longitudinal direction of the locomotive. Generally, said fans consisted of screw fans of known type operating in a diaphragm arranged in the plane of the fans and separating the suction side of the fan from its pressure side, said diaphragm consisting preferably of a sheet metal plate secured to the steam distributing pipes.

Such condensers have usually been provided with means to distribute the steam to the different cooling elements, said means consisting, for instance, of steam distributing pipes in which the cooling elements have been inserted either directly or by means of collecting chambers common to a plurality of such cooling elements.

As is well known, the extension of the locomotive in all directions is limited by the so called loading gauge, and for this reason it has been difficult to place these steam distributing pipes in the most suitable manner whilst maintaining at the same time the size of the fans.

The present invention refers to condensers of this type, and has for its object to provide means whereby the steam may be distributed to the elements in a more suitable manner than has hitherto been possible, without decreasing the dimensions of the fans. According to the invention, the steam distributing means consist of one or more chambers or boxes disposed at the same level as the fans and having a shape conforming to the necessary clearance with respect to the periphery of the fans. Each steam distributing chamber preferably consists of a plurality of chambers preferably made of cast iron.

An embodiment of the invention is shown by way of example in the accompanying drawing, in which Fig. 1 is a plan view of a

condenser according to the present invention, whereas Fig. 2 is a section on the line II-II in Fig. 1.

The condenser shown comprises an air cooled part consisting of two groups of cooling elements 1 and 2 placed on opposite sides of a vertical plane of symmetry through the condenser, and a liquid receptacle 3. In the embodiment shown the cooling elements are placed along the sides of the condenser, and communicate with the lower part of said receptacle by means of collecting chambers. Arranged above the receptacle are fans 8, 9, 10 driving the air necessary for cooling through the air cooled part between the elements. The passage of the air is indicated in Fig. 2 by the arrows 11 and 12.

According to the invention, the means for distributing the steam to the several elements consist of one or more chambers 4 and 5 arranged at the same level as the fans 8, 9 and 10. The chambers have a shape conforming to the periphery of the fans whilst providing for necessary clearance. Consequently, the chambers will perform the function of the diaphragms previously used and also that of the steam distributing pipes. The chambers have, preferably, the same height as the wings of the fans. In the embodiment shown, each steam distributing chamber consists of a plurality of chambers 4^a, 4^b, 4^c, 4^d and 5^a, 5^b, 5^c, 5^d respectively. These chambers are preferably made of cast iron and provided with ribs by which they are connected with each other by means of bolts. The chambers may communicate with each other, but preferably they are entirely separate, in which case it is not necessary to provide any packing means between the different chambers.

As shown in Fig. 1, the integrating chambers have such a shape that their cross section decreases according to the cooling passage of the steam into the elements. Of course, by this means a more uniform distribution of the steam to the elements will be effected.

By means of an arrangement according to the present invention several important advantages are gained. The chambers are preferably cast from the same material as the condenser, and, consequently, the same

conditions of expansion prevail in said chambers as in the remaining part of the condenser. By this means the clearance between the fans and the chambers may be 5 made smaller than has hitherto been possible between the fans and the diaphragms, which diaphragms do not follow the variations in temperature in the condenser, but instead have a temperature different from 10 that of the other parts of the condenser. According to the invention it will also be possible to insert the collecting chambers of the cooling elements into the distributing chambers in a more suitable manner, as said 15 distributing chambers, made of cast iron, may be more easily prepared for the insertion of the collecting chambers, whereby the manufacture of the condenser will be facilitated.

20 What we claim is:—

1. In a condenser for locomotives, condenser elements arranged on opposite sides of a vertical plane of symmetry through the condenser, fans for passing air in heat exchange relation to said condenser elements, and means for distributing steam to the condenser elements comprising chambers in the same plane as the fans and shaped to conform to the periphery of the fans.
2. In a condenser for locomotives, condenser elements arranged on opposite sides of a vertical plane of symmetry through the condenser, fans for passing air in heat exchange relation to said condenser elements, and means for distributing steam to the condenser elements comprising a plurality of contiguous chambers in the same plane as the fans and shaped to conform to the periphery of the fans.
3. In a condenser for locomotives, condenser elements arranged on opposite sides of a vertical plane of symmetry through the condenser, fans for passing air in heat exchange relation to said condenser elements, and means for distributing steam to the condenser elements comprising a plurality of contiguous chambers, in the same plane as

the fans and shaped to conform with the periphery of the fans, a liquid receptacle, and steam pipes leading from said liquid receptacle to said chambers, said liquid receptacle being disposed below said chambers and communicating with said condenser elements for drainage of condensate from said condenser elements.

50

4. In a condenser for locomotives, condenser elements arranged on opposite sides of a vertical plane of symmetry through the condenser, fans for passing air in heat exchange relation to said condenser elements, and means for distributing steam to the condenser elements comprising chambers in the same plane as the fans and of substantially the height of the fan blades, and shaped to conform to the periphery of the 65 fans.

60

5. In a condenser for locomotives, condenser elements arranged on opposite sides of a vertical plane of symmetry through the condenser, steam distributing chambers 70 communicating with said condenser elements and adapted to form a roof for said condenser, said chambers having openings therein, and fans positioned within said openings for passing air in heat exchange 75 relation to said condenser elements.

70

6. In a condenser for locomotives, condenser elements, fans for passing air in heat exchange relation to said condenser elements, and means for distributing steam to the condenser elements comprising chambers in the same plane as the fans and shaped to conform to the periphery of the fans, said chambers and said condenser elements having substantially the same coefficient of expansion.

80

In testimony whereof we affix our signatures.
